GUN COOLING APPARATUS

James R. Stephenson, Dayton, Ohio, assignor to
 General Motors Corporation, Dayton, Ohio, a
 corporation of Delaware

Application February 13, 1943, Serial No. 475,706

4 Claims. (Cl. 89—14.1)

This invention relates to gun cooling apparatus and more particularly to apparatus for cooling the barrel of a rapid firing gun such as a Browning machine gun.

It is an object of this invention to simplify the design of the cooling jacket for a machine gun.

Another object of this invention is to eliminate the need for any moving parts in the cooling jacket.

Still another object of this invention is to reduce the cost and the weight of the cooling jacket.

Further objects and advantages of the present invention will be apparent from the following description, reference being had to the accompanying drawings, wherein a preferred form of the present invention is clearly shown.

In the drawings:

Fig. 1 is a side elevational view of a machine gun provided with a cooling jacket constructed in accordance with my invention;

Fig. 2 is a vertical sectional view on an enlarged scale;

Fig. 3 is a fragmentary elevational view of the vent pipes with parts broken away;

Fig. 4 shows the relative position of the venting apparatus with respect to the water in the water jacket when the gun is placed to be fired upwardly;

Fig. 5 shows the water level while firing on the level;

Fig. 6 shows the water level while firing downwardly; and

Fig. 7 is a fragmentary sectional view taken on line 7—7 of Fig. 2.

The water used for cooling the barrel of a machine gun is frequently obtained from swamps and the like and for that reason often contains much foreign matter which would interfere with any automatically operated valve mechanism placed in the water circuit. In the arrangement disclosed herein the usual valves located between the inlet and the outlet of the cooling jacket have been eliminated.

Referring now to Fig. 1 in which I have shown a preferred embodiment of my invention reference numeral 10 designates a standard Browning machine gun. Reference numeral 12 generally designates a cooling jacket which surrounds the barrel 14 of the gun. In Fig. 2 I have shown the relationship of the cooling jacket 12 to the barrel 14. As shown therein the cooling jacket comprises a main cylindrical portion 16 which surrounds the barrel 14 throughout the major

portion of the barrel. End caps 18 and 20 cooperate with the ends of the cylindrical portion 16 and the barrel mechanism so as to form a watertight chamber 22 surrounding the barrel.

Since the barrel of a machine gun becomes very hot during operation of the gun the water supplied to the chamber 22 is inclined to vaporize unless a large enough quantity of water is continuously circulated through the chamber 22.

10 Inasmuch as the water supply is often very limited, provision must be made for allowing the vapor to escape without the loss of any appreciable amount of water irrespective of whether the gun is pointed upwardly, downwardly or horizontally. In order to provide for circulation of the water through the chamber and in order to provide for the escape of vapor from the chamber I have provided a simple venting apparatus in the form of an adapter which includes a casting 32 secured to the inner wall of the cylinder 16, a U-shaped tube 24 having its one end 26 open to the interior of the chamber 22 and having its other end 28 communicating with the outlet chamber 30 formed in the casting 32 and a straight tube 34 which surrounds the one leg of the U-shaped tube 24 and has its one end 36 communicating with the interior of the chamber 22 at the forward end of the barrel and has its other end 38 communicating with the outlet chamber 30 and outlet opening 31 provided in the casting 32.

35 The ends of the tube 24 are brazed or otherwise secured to the casting 32 so as to provide water-tight joints therewith. Likewise the tube 34 has its one end brazed or otherwise secured to the casting 32 whereby the casting 32 together with the tubes 24 and 34 form a unitary assembly which may be secured to the inner wall of the cylinder 16 in any suitable manner such as by brazing.

40 In order to facilitate slipping the cooling jacket onto the barrel of the gun, I have provided a sheet metal guide member 37 which is brazed or otherwise secured to the end cap 20. Reference numeral 40 designates the usual packing assembly which allows the barrel of the gun to recoil during operation. The construction of the assembly 40 has not been changed and corresponds to the structure used prior to my invention and therefore needs no further description. The end caps 18 and 20 may be brazed or otherwise secured to the cylindrical shell 16. By virtue of applicant's simple trouble-free construction the need for replacing any of the parts of the cooling jacket has been substantially eliminated

with the result that it is more practical to replace the entire cooling jacket in the event of damage kinds of supply parts and making the individual parts removable from the assembly.

The forward end of the tube 34 may be brazed or otherwise secured to the end cap 20 at 50 in order to more rigidly support the front end of the venting apparatus.

Reference numeral 42 designates a drain plug which may be used for draining the water jacket when not in use. Water is supplied to the cooling jacket through the inlet 44 provided with a plug 45 which may be used for closing the inlet 44 whenever desired. The cooling jacket may be supplied with water from any suitable source. Thus it is common to provide a pump which supplies a steady stream of water to the cooling jacket. Under certain circumstances the amount of water may be limited, in which case only a small amount of water is supplied to the jacket and most or all of this is vaporized and the vapor leaving the jacket through the outlet 30 is either wasted or recondensed and returned to the inlet 44. In cold climates a suitable anti-freeze may be used in the cooling jacket, in which case it would be desirable to recondense the anti-freeze so as to be able to use it over and over again without any loss. Since the details of the pumping equipment and the condensing equipment form no part of my invention, this equipment has not been shown in the drawings.

By virtue of the construction described hereinabove, when the gun is firing upwardly the vapor may escape from the cooling jacket by passing downwardly through the tube 34 and out through the outlet 31. In this position of the gun the water will not drain out through the tube 24 since a portion of the tube projects above the water level. When the gun is pointed horizontally the vapor may escape through either or both of the vent tubes as the inlet to each tube is above the required water level as shown in Fig. 5. As shown in Fig. 6, when the gun is pointed downwardly the vapor may escape through the tube 24 but no water will escape since the inlet 26 of the tube 24 is above the water level and the outlet of the straight tube 34 is also above the water level.

While the form of embodiment of the invention as herein disclosed constitutes a preferred form it is to be understood that other forms might be adopted, as may come within the scope of the claims which follow.

What is claimed is as follows:

1. In combination with an automatic firearm having a barrel, a cooling jacket for said barrel extending substantially the full length of said barrel, and means for venting the interior of said jacket comprising a vent opening adjacent one end of said jacket, a first vent tube communicating

with said opening and having an inlet adjacent the other end of said jacket, and a substantially U-shaped tube extending substantially the full length of the jacket and having an outlet communicating with said vent opening and having an inlet at the end adjacent said vent opening, one of the arms of said U-shaped tube being disposed within said first vent tube.

2. In combination with an automatic firearm having a barrel, a water jacket surrounding said barrel, a water inlet opening provided in the wall of said jacket, a water and/or vapor outlet opening provided in the wall of said jacket, a fitting disposed within said jacket having a first threaded opening communicating with said inlet opening and having a second threaded opening communicating with said outlet opening, said fitting including a chamber communicating with said second threaded opening, a U-shaped tube extending substantially the full length of said water jacket and having its one end communicating with said chamber and having its other end communicating with the space between said jacket and said barrel, and a second substantially straight tube having its one end communicating with said chamber and having its other end communicating with the space between said water jacket and said barrel, the inlet of said substantially straight tube and the inlet of said substantially U-shaped tube being disposed adjacent opposite ends of said water jacket.

3. In combination with an automatic firearm having a barrel, a water jacket surrounding said barrel, a casting within said jacket having a first passage for supplying water to said jacket and a second passage for venting said jacket, a substantially U-shaped tube having its inlet end communicating with the inside of said jacket and having its other end communicating with said second passage, and a substantially straight tube having its inlet end communicating with the inside of said jacket at a point remote from the inlet end of said U-shaped tube and having its outlet end communicating with said second passage, both of said tubes being disposed substantially wholly above the upper side of said barrel.

4. In combination with means forming an elongated tiltable chamber, means for venting the interior of said chamber comprising a vent opening, a first vent tube communicating with said opening and having an inlet adjacent one end of said chamber, and a second vent tube having an outlet communicating with said vent opening and having an inlet at the other end of said chamber, said second vent tube having a U-shaped bend therein and having one arm of the U disposed within said first vent tube.

JAMES R. STEPHENSON.
